Primary Examiner — Cynthia Ramirez(74) *Attorney, Agent, or Firm* — Nixon & Vanderhye(57) **CLAIM**

The ornamental design for a conveyor, as shown and described.

DESCRIPTION

FIG. 1 is a front and left side view of a conveyor showing the new design;

FIG. 2 is a front, left side, and top perspective view thereof; and,

FIG. 3 is a front elevation view thereof.

The broken lines shown in the figures are to show portions of the conveyor, which form no part of the claimed design.
